UNITED STATES PATENT OFFICE.

JOHN B. GENIN, OF ST. ALBANS, VERMONT.

AUTOMATIC TRAIN-PIPE COUPLING.

Application filed May 19, 1920. Serial No. 382,507.

To all whom it may concern:

Be it known that I, JOHN B. GENIN, a citizen of the United States of America, residing at St. Albans, in the State of Vermont, United States of America, have invented certain new and useful Improvements in Automatic Train-Pipe Couplings; and I do hereby declare that the following is a full, clear, and exact description of the invention, such as will enable others skilled in the art to which it appertains to make and use the same.

The present invention relates to automatic train pipe-couplers for connecting adjacent ends of the pipe lines for air and steam on railway cars, and, is an improvement over my previous Patent No. 1,327,031, dated January 6th, 1920.

An object of this improved form of automatic train pipe-coupler is to provide means for effecting the connection of such couplers either on curved or straight railway beds, and, for maintaining thereafter an absolutely tight joint whether cars pass around curves or not, or, whether the coupling members should be, for any reason, slightly displaced with reference to each other.

Another object of this invention is to provide an automatic train pipe-coupling device that will effectively yield to shocks, vibrations or any other irregularity that may arise from the motion, of whatever nature it may be, of a train, and, which is simple in construction, easy and cheap to manufacture, and, as practical and effective in application as is consistent with the requirements of modern transportation.

The invention further contemplates the provision of a device for effecting the connection of the adjacent ends of the air and steam hose on railway cars when two of said cars, to be coupled, are not both provided with the usual coupling device, and, the adapter hereinafter disclosed, as embodying the means for effecting such connections, forms an integral part of the present application.

With the above and other objects in view which will hereinafter appear as the description continues, the invention consists of the novel features of construction, combination and formation of parts as will be herein-after more fully described.

For a full understanding of the invention and the merits thereof, and also to acquire a knowledge of the details of construction

and the means for effecting the result, reference is now had to the following description and accompanying drawings, in which:

Figure 1 is a side elevation of the coupling device as applied;

Figure 2 is a plan view of the couplers;

Figure 3 is a front elevation of one of the coupling members;

Figure 4 is a vertical section through one of said couplers;

Figure 5 is a front elevation of the adapter used as an interchangeable coupler-head; and,

Figure 6 is a side elevation showing the adapter coupled with a stationary coupler-head.

Referring to the above drawings, where like parts therein and throughout the corresponding description are referred to and indicated by the same reference characters,

A main bracket 1 of spring steel is adapted to the drawbar or shank of the automatic car couplers by means of set screws, bolts and nuts, or U-bolts, clamping plates and nuts.

To the lower extremity of the main bracket 1 is rigidly attached a guide block 2 having a rectangular slot therein registering with a similar slot cut through the lower end of said main bracket.

Attached to the lower end of the upper portion of said main bracket is a threaded flanged stud or boss 3 on which is mounted a spring seat 4 and locking nut 5.

Mounted on the lower end of the main bracket and passing through the same and through the above mentioned attached guide block is a pipe-coupler shank 6 having at one end a rectangular section (A) to loosely fit said slot in said guide block and main bracket and to slide longitudinally therein, and, having at the opposite end a circular section (B) reduced in diameter for a portion of its length and terminating in a shoulder to support or act as a stop for a spring seat or follower block 7, and, having its forward extremity (C) further reduced in diameter and threaded to receive the coupler-head female ball and socket joint connection 8.

Near the extremity of the rectangular end (A) of the pipe-coupler shank 6 is mounted a spring seat 9 slotted to receive said shank, and secured thereto by a headed pin 10 and split cotter. Vertically mounted upon this spring seat is a helical spring 11 bearing

at its upper end against the above described adjustable spring seat 4 mounted on the flanged stud or boss 3 at the upper rear end of the main bracket 1.

- 5 Mounted upon and encircling the forward or cylindrical portion of the pipe-coupler shank 6 is a shock absorbing helical spring 12 taking bearing at its foremost end against the follower block or spring seat 7 above referred to as being attached to the coupler shank and at its rear end against the guide block 2 through the medium of a spring follower block 2^a having a convex face bearing against said guide block 2.
- 15 To maintain the required degree of compression on the shock absorbing spring 12, and to retain coupler shank and head in their normal position, a combined stop block and shank aligning bracket 13 is fitted to the rear end of coupler shank 6, and, is connected thereto by a headed pin 14 and split cotter.

Attached to coupler shank 6 by means of a ball connection 15 fitting into socket 8, is 25 the coupler head 16.

Coupler head 16 is provided with a conical spigot 17 in one cheek, and, a corresponding socket 18 in the opposite cheek, which spigot and socket engage with similar and 30 opposite sockets in the coupler heads on other cars when brought together for coupling, thereby guiding together all apparatus for proper registration, it being noted in this connection, that the sockets and spigots 35 upon each of the coupler heads 16 are arranged laterally of the respective ball or spherical connections 15 and in horizontal alignment therewith, the base portions of the several spigots being curved outwardly 40 and slightly enlarged whereby to brace the connections 15 against material lateral stress upon relative movement between the heads and also to ensure tight engagement between the spigots and their respective sockets so as to avoid detrimental vibration or 45 rattling during movement of a train over a course. Coupler head 16 is further provided with three perforations, recessed in the front of the coupler head into which 50 perforations and recesses are fitted sleeves 19, 20 and 21, threaded at the small end and fitted with nuts for rigidly holding sleeves in place. The threaded portion of the sleeves 19, 20 and 21 are made of sufficient 55 length to project through the nuts, and to these projections connection is made to the train-pipes of the car by suitable metal or other flexible hose pipe, for both the brake and signal air pipes, and, for the steam 60 pipe. The steam pipe connection is in the lowest position in the coupler head and is designated 21.

The forward or flanged ends of sleeves 19 and 20, (for air) are concentrically recessed 65 and undercut to receive and rigidly hold

in position special gaskets 22 and 23 of rubber or other elastic material for the purpose of engaging with similar contrivances attached to other cars, thereby making a perfect air tight joint as soon 70 as such gaskets meet.

The forward or flanged end of sleeve 21 is spherically recessed and fitted therein, moulded or machined to the correct shape, is a gasket 24 of hard rubber, vulcanite or 75 other suitable material for making a steam tight joint when cars are coupled, as in the case of air connections.

This gasket 24 is held in place by a simple spring clip 25 which, while holding gasket 80 in place permits the movement necessary to insure a perfect joint.

Fitted to the coupler head immediately below the steam pipe sleeve 21 and having connection to the interior thereof, is a drain 85 valve 26 for the removal of condensed steam.

In the hereunto annexed drawings, Figures 5 and 6 serve to illustrate more particularly a preferred form of an adapter or portable coupling for use with the improved 90 automatic train pipe-coupler, in coupling cars fitted with said coupler to cars not so fitted, but, equipped with the standard hose connections.

Said adapter is so designed that it may 95 readily be attached to the automatic pipe-coupler heretofore described and held secured thereto by means of clamping devices.

The portable coupling 32 consists of a flat plate having three bosses 33 and 34 in alignment with its vertical major axis, and these bosses are equipped with removable nipples 35, 35' and 36 similar in every respect to the nipples 19, 20, and 21, so that it is thought unnecessary to repeat the description of these nipples.

The upper boss 33 is formed with a curvilinear hood 37 which engages the upper boss of the coupling member, so that the latter thus supports the adapter 32 effectively.

The upper portion of the portable coupling 32 is of inverted pear-shape so that it will not project beyond the edges of the body-portion 16 of the coupling when the said portions are in engagement, and the 115 lateral edges of the adapter 32 are formed with semicircular recesses 38 and 39, the former of which gives the necessary clearance to the conical projection 17 when the portions 32 and 16 of the coupling are engaged.

The recess 39 will give a proper balance to the portion of the coupling 32 and this recess otherwise performs no function, because it is not required to clear a conical projection 18, since the said projections are on opposite faces of the coupling members 16.

A pair of guide pins 40 may be carried by the coupling portion 16 and this will facilitate guiding the portions 32 and 16 of 130

the coupling into proper engagement in which the nipples 35, 35' and 36 will be in alignment with the nipples 19, 20 and 21 respectively.

5 The portable coupling portion is provided with a pair of orifices 41 through which the T-shaped screws 42 pass to be threaded into the portion 16 of the coupling, and the screws hold the coupling in assembled position so that coacting gaskets of corresponding nipples are in alignment and make fluid-tight joints.

In Fig. 5 the dotted lines indicate the relative position of certain prominent parts 15 of the portion 16 of the coupling, which portion is not shown because it would render the figure confused.

It should be noted that as the portion 20 16 supports the portion 32 of the coupling, the joints of coacting gaskets cannot be broken by jarring or when the train is taking a curve. It should also be observed that all projections are parallel with the longitudinal axis of the bosses and nipples, 25 and there are no lateral projections to foul any appendages of the railway cars.

In the accompanying drawings and the foregoing description has been disclosed a simple and preferred form of the invention, 30 it being, however, understood that no limitation is necessarily made to the precise structural details therein exhibited, but the right is hereby reserved to any changes, alterations or modifications to which recourse 35 may be had that come within the scope of

the following claim without departing from the spirit of the invention or sacrificing the efficiency of the same.

Having thus fully described my invention, what I claim as new and desire to secure by Letters Patent is:—

A coupling of the character described, comprising complementary integral cast coupling heads of substantially triangular formation, formed with opposed conical spigots 45 on the opposite sides thereof and corresponding sockets in the remaining sides thereof, said spigots and sockets being arranged adjacent the angles at the opposite sides of their respective triangularly shaped heads, 50 the base portions of said spigots being slightly enlarged and curved outwardly whereby to ensure their snug reception in their respective sockets, said heads having aligning openings therein, circular conduit receiving 55 collars extending laterally from the heads and surrounding said openings, means within said collars formed on their inner ends with packing receiving seats, spherical heads cast integral with and extending outwardly 60 from said heads arranged in horizontal alignment with said spigots and sockets and intermediate the same, and brackets for receiving and supporting said spherical heads and their respective coupling heads whereby 65 to permit of universal relative adjustment between the latter.

In witness whereof I have hereunto set my hand.

JOHN B. GENIN.
